UNITED STATES PATENT OFFICE.

JOHN H. GORMAN, OF SALISBURY, NORTH CAROLINA.

COLLAPSIBLE HOGSHEAD.

1,112,001.

Specification of Letters Patent. Patented Sept. 29, 1914.

Application filed May 16, 1913. Serial No. 768,046.

To all whom it may concern:

Be it known that I, JOHN H. GORMAN, a citizen of the United States, residing at Salisbury, in the State of North Carolina, 5 have invented certain new and useful Improvements in Collapsible Hogsheads, of which the following is a description.

Figure 1 is a perspective view of the hogshead complete and erected; Figs. 2, 3, 4 and 10 5 detail views of the manner of applying and fastening the hoops; Fig. 6 a detail perspective view of a cam lever employed to connect the adjacent ends of the hoops; Figs. 7, 8 and 9 detail views of the hogshead collapsed, ready for storing and shipping, Fig. 9 being a sectional view taken on the line 9—9 of Fig. 7; Figs. 10 and 11 detail views showing the folding bottom or lower head of the hogshead; Fig. 12 a detail 15 perspective view of one of the supporting stops for the bottom; Figs. 13 to 18, inclusive, detail views of the expanding head.

The object of this invention is to so construct the hogshead that it may be readily 25 assembled or erected and also readily disassembled or collapsed at the place of unpacking, the parts in their collapsed or disassembled condition being brought together in such a manner as to occupy but a small 30 space and therefore permit them to be conveniently stored or shipped, as more fully and hereinafter set forth.

The body consists of the usual staves *a*, and a pair of special staves *b*. The usual 35 staves *a* are fastened together at their upper and lower ends by pairs of hoops *c*, these staves being fastened together in two halves or groups which, together with the special staves *b*, constitute the vertical wall 40 of the hogshead.

At one side of the hogshead the ends of the hoops are connected to short straps *d* by vertical links *e*, and said straps *d* are rigidly secured to the intermediate spacing 45 stave *b*. The inner corners of the special or spacing staves *b* are beveled off at *e*, and the adjacent corners of the adjacent main staves *a* are beveled off at *f*, for the purpose hereinafter set forth.

50 At the side of the hogshead diametrically opposite to the link connections *e* the spacing stave *b* is hingedly connected to the respective pairs of hoops *c*, by links *g* and *h*. The links *g* connect the ends of the hoops *c*

to short straps or plates *i* fastened to the 55 spacing stave *b*, while the links *h* connect the other pair of hoops *c* to said spacing stave *b* through the medium of a swinging lever *j* pivotally mounted on the said short straps *i*.

The levers *j* and links *h* are for the purpose of permitting the enlargement of the diameter of the stave structure. Each link *h* consists of a vertical bar *k*, which is pivoted in loops formed in the ends of hoops *c*, and lateral arms *l* connected to the ends of 60 said vertical bar *k*, and being connected at their outer ends by a bent bar *m*. Midway the length of the bar *m* said bar passes through a vertical slot *n* in the lever *j*, and the inner end of the lever *j* is provided with 65 oppositely projecting pins *o* which are pivotally mounted in loops formed at the ends of the short straps *i*. The slot *n* is closed at both ends. It will be observed that by swinging the lever *j* outwardly on its pivots 70 *o* a space will be formed between the spacing stave *b* and the adjacent main stave *a*, thus enlarging or expanding the stave structure 75 to the extent of said space. When the levers *j* are swung inwardly, that is, toward the face of the spacing stave *b*, the stave adjacent to the said spacing stave is brought close up to the adjacent edge of the spacing stave *b*, thus closing the stave structure.

The bottom of the hogshead consists of 80 two semi-circular sections *p*, pivotally connected together along their straight edges by hinges *q*, whose pintles *r* are arranged at the under side of the bottom so as to permit the bottom sections to swing inwardly in 85 collapsing. The two semi-circular sections are connected by means of link hinges *s* to the adjacent inner faces of the stave structure. Spanning the joint between the two sections of the bottom are a series of cleats *t*, 90 each of these cleats having one of its ends connected rigidly to one of the sections of the bottom, and its other end free from the opposite bottom section. In the drawing, I have illustrated the middle cleat as being 95 rigidly attached to the right-hand section of the bottom and free from the left hand section, while the other two cleats are arranged reversely. When the bottom is in position for packing, it rests upon a series of inwardly projecting lugs *u*, suitably fastened 100 to the main staves *a*.

The head of the hogshead is constructed

so as to be expanded and contracted circumferentially, and it will be understood that it is within the scope of my invention to use any form of head adapted to thus expand and contract.

In the form of head I have illustrated, I employ four sectors a' and a series of four radial wedges b' , these wedges tapering from the center to the rim of the head and abutting against the correspondingly inclined adjacent edges of the sectors a' . With this construction, it will be observed that by forcing the wedges outwardly in a radial direction, the sectors or segments a' will be forced outwardly and thus increase the diameter of the head; while by drawing the wedges inwardly, the sectors will be free to move inwardly to thus contract the head.

To connect the wedges and the sectors and to simultaneously move them inwardly and outwardly, I prefer employing the following devices: Each sector and each wedge is guided in its radial movements by means of slots c' and pins d' , the latter being rigidly carried by a disk e' located on the under side of the head. Rotatably mounted in any suitable manner on the disk e' is a top disk f' , a suitable angular part g' being provided for the application of a wrench for rotating the disk f' in either direction. Depending from the underside of the disk f' is a series of pins h' , each of which works in a slot i' at the inner end of one of the wedges b' . Each slot i' is formed in a casting rigidly fastened on the inner end of the wedge, and each of these castings is provided with a pair of lateral lugs j' which engage behind vertical pins k' carried by the sectors a' . Two of the lugs j' engage behind each one of the pins k' , these oppositely projecting lugs overlapping each other. Each of the pins k' is attached to its sector a' by means of a shank l' which is carried by a metal plate m' fastened to the inner edge of the sector. It will be observed that with this arrangement of devices, the turning of the disk f' in one direction will cause the wedges to force the sectors outwardly, while by turning the disk in the opposite direction, the wedges, as well as the sectors, will be drawn inwardly.

In erecting and packing the hogshead, the two stave sections are partly separated and then the bottom sections are forced downwardly until they completely spread the stave structure and are located in alignment, as shown in Fig. 11. In thus forcing the bottom sections downwardly, the attendant may apply the power (preferably by standing or jumping) upon the upwardly projecting free ends of the cleats t . When the bottom sections are being thus forced downwardly it will be seen that the free ends of these cleats project upwardly

in opposite directions and serve the function of a series of levers, whereby a considerable force can be applied, to the end that the hogshead will be distended under considerable pressure, thus very strongly bracing the bottom of the hogshead. It will be observed also that by thus fastening these lever cleats upon the inner face of the bottom sections, the weight of the contents of the receptacle will be brought to bear directly upon these cleats and will thus insure the bottom sections being held in their locked or spread position.

After the hogshead has been packed then the sectional head is introduced and expanded so that the outer edges of its sectors engage in the grooves or in the inner faces of the staves. With the wedge arrangement shown and described, I have been able to exert great power in locking the head in the grooves, thus fully expanding the hogshead at the upper end thereof by flexible metal hoops under powerful tension. Thus, when the bottom and the head are thus extended, it will be seen that the hogshead is thoroughly braced and is of such great strength that it can be heavily loaded and transported without injury.

I have especially designed my hogshead for the transportation of leaf tobacco, which is packed into the hogshead with a very heavy pressure and, therefore, requires that the hogshead shall be very strongly braced in every direction. In unpacking leaf tobacco, the head is first removed by drawing in the wedges in the manner set forth; and the hogshead is inverted, whereupon by simply expanding the stave structure by swinging the levers j outwardly, the hogshead may be lifted off the mass of tobacco, leaving the mass standing on the floor uninjured and undisturbed by the unpacking operations.

To indicate to the attendant where the wedges are expanded to their fullest extent, I have attached to one of the wedges the spring clip a^2 and arranged the same so as to overlap the top disk f' , this disk being provided with a pin b^2 which is intended to extend into a hole in the clip b^2 when the wedges are projected. Any other suitable means may be employed for thus indicating the position of the wedges. The link hinges s provide for the necessary lost motion between the stave structure and the bottom in order that the stave structure may be swung away from the bottom a limited distance, this distance being just sufficient to free the mass of tobacco or other material from the stave structure to permit the stave structure to be lifted off the mass when it is inverted. It will be observed also that when the stave structure is thus expanded, the levers j will not be disconnected from the links h but will be connect-

ed thereto by reason of the use of the closed slot *n*. This is advantageous in that it prevents the two halves of the stave structure separating from the spacing staves *b*, and thus contributes to ease of handling and tends to lessen injury during transportation.

When it is collapsed, it will be seen that the two halves of the stave structure straighten out and form the opposite sides of the box-like structure, the two other sides of this structure being formed by spacing staves *b*, as shown in Figs. 7, 8 and 9. The bottom sections fold into this box-like structure and serve to brace and support its longer sides, as shown in Fig. 8. As thus collapsed, it will be seen that the hogshead occupies but a small space and thus renders it easily packed and shipped. The box-like structure, together with the inclosing therein of the bottom sections, insures against breakage in the rough handling incident to transportation and, as shown by dotted lines at the top of Fig. 7, the head may be inserted partly into one end of the box-like structure for convenience in packing and shipping.

As contributing to safety in transporting the collapsed structure, it will be seen that the large walls of the box-like structure are flexible when collapsed.

It is obvious that the features of my invention may be embodied in stave structures of smaller dimensions than hogsheads, such as barrels. Therefore, it will be understood that my claims are not limited to hogsheads.

It will be observed that a feature of importance in my structure is the employment of a single vertical link at each joint in each hoop where it crosses the joint between a main stave *a* and the special or spacing stave *b*. It will be observed that each link connects the main part *c* of each hoop to the short part *d* (or *i*) affixed to the special or spacing stave, and that the horizontal bars of the link extend across the joint between said staves, the vertical bars of the link serving as the pintles, whose axes are set back a distance from the joint between said joint between the staves. With this construction the links as well as the short straps *d* and *i* are brought into the direct circumferential line of tension of the hoops, thereby enabling the link connections to withstand very heavy strains without tending to twist the links or pull off the short straps *d* and *i* and also all tendency to dislodge the special stave *b* when the stave structure is spread and filled. A further advantage is that these link connections give an ease and freedom of movement which insures the closing of the joints between the special stave and the adjacent staves whether the structure be opened out or be collapsed, as shown in Fig. 8, the links when the struc-

ture is collapsed being free to extend across the corners of the collapsed box-like structure, as shown in said Fig. 8.

I claim:

1. A stave structure consisting of two main sections each of which consists of staves flexibly connected together, means for hinging these two main sections together at their adjacent edges, these means embodying devices whereby the adjacent edges of the main sections may be separated a limited distance to thus increase the diameter of the stave structure without disconnecting said adjacent edges of the main sections, a removable top or head, and a bottom, and lost-motion means connecting said bottom to the main sections, these connecting means being so constructed as to permit the main sections to have an outward movement independently of the bottom when the main sections are expanded in the manner set forth.

2. A receptacle consisting of a collapsible stave structure, a removable head, a bottom consisting of sections hinged to the stave structure and to each other and adapted to swing inwardly into the stave structure, and cleat bars each rigidly fastened at one end to the inner face of one of said sections and having its unattached end extending across the joint between the sections, whereby the free end portions of said cleats may be used as levers in spreading the sections of the bottom and whereby also the weight of the contents of the receptacle will aid in holding the sections spread.

3. In combination, a removable head, an expandable and contractible stave structure, a bottom constructed of hinged sections adapted to fold inwardly, and link hinges connecting said sections to the stave structure, the link hinges permitting the stave structure to be expanded without disconnecting the same from the bottom.

4. In combination, a stave structure and means whereby its diameter may be expanded and contracted a limited distance, said means forming a permanent connection between the parts of the stave structure, whereby the stave structure may be expanded without disconnecting its adjacent edges, the bottom consisting of sections hinged together and adapted to fold inwardly, and link hinges connecting said sections to the stave structure.

5. A collapsible receptacle, consisting of a stave structure comprising two main sections and two spacing staves forming end walls when the structure is collapsed, the other two walls being formed by said main sections, the inner corners of the main sections as well as the spacing staves being correspondingly beveled, a removable head, a sectional bottom hinged to the said main sections and adapted to fold into the box-

like receptacle formed by said main sections and said spacing staves; flexible hoops connecting the staves of said main sections and additional short hoop sections attached to the spacing staves, and links connecting the adjacent ends of said hoops, each of said links extending across one of the joints between the spacing stave and the adjacent stave of the main section and being pivotally

connected to the hoop sections, for the purposes set forth.

In testimony whereof I hereunto affix my signature in the presence of two witnesses.

JOHN H. GORMAN.
